UNITED STATES PATENT OFFICE.

ADMIRAL S. KNOTT, OF COLUMBUS, OHIO.

AUTOMATIC ADVERTISING PROJECTION APPARATUS.

Application filed September 15, 1925. Serial No. 56,457.

My invention relates to improvements in automatic advertising projecting apparatus of the type where a series of interchangeable slides, bearing advertising matter, are intermittently positioned in the optical axis of a stereopticon machine for projection upon a screen.

The invention relates particularly to machines of this character designed for out-of-door advertising, requiring the minimum of attention and adjustment over long periods of time.

Such advertising projecting machines are usually positioned in out of the way places, such as for instance, on the roofs of buildings, for projection upon screen billboards which are visible from the streets and highways below. It is therefore quite difficult to attend these machines and it is therefore essential that the mechanism be constructed to withstand jars and other disturbances occasioned by exposure to the elements, without impairing the operation of the machine, or disturbing the adjustment of the focusing apparatus.

It is therefore the primary object of my invention to provide a simple, compact, and rigidly constructed, portable stereopticon machine, which is adapted to operate automatically over long periods of time, without attention for adjustments and repairs.

A further object of my invention is to provide readily accessible means whereby the automatic mechanism, which is employed to intermittently advance the endless slide carrier, may be disconnected from the slide carrier drive. The endless slide carrier may then be easily moved by hand in either direction to bring the individual slide holders into any desired position for insertion or removal of a slide, without changing the timing of the slide carrier when the disconnecting means is released.

A further object of my invention resides in the formation of the endless slide carrier conveyor and the slide carriers, whereby each slide is accurately timed and positively held in parallel relationship during their intermittent travel through the optical axis of the stereopticon machine.

A further object relates to the formation of the individual slide holders which are

formed to close the space between each pair of slides during the travel of the slide conveyor through the optical axis of the stereopticon, and thereby exclude the passage of interfering light on the screen.

A further object of my invention resides in the formation of the supporting frame on which each element of the machine is adjustably mounted and compactly arranged, whereby the device may be bodily moved from place to place and set up for continuous operation, without disturbing the adjustment of the various elements.

A still further object of my invention is to provide, as an attachment to a stereopticon machine of this character, a separate optical projection apparatus as a unit. The unit is adjustably mounted on the frame of the main stereopticon and adapted to be operatively connected therewith for simultaneous adjustment to project upon a screen an animated or moving light border around and concentric with the optical projection of the main stereopticon.

Referring now to the drawings on which similar reference characters indicate similar parts:

Fig. 1 is a perspective view of my improved stereopticon machine, showing in detail the construction of the supporting frame and the relative arrangement of elements adjustably mounted thereon. It will be noted that the animated light border projection unit is shown adjustably mounted on the frame and operatively connected to automatically function with the elements of the main stereopticon.

Fig. 2 is a side elevation of the front portion of the main stereopticon machine, partly in section, showing the mounting of the condenser lenses between the spaced legs of the supporting frame and the details of the intermittent driving mechanism for the endless slide conveyor. The mounting for the animated light border projection unit is also shown in this figure.

Figure 3 is a sectional view taken on line 3-3 of Fig. 2, to show the clutch and the manual operating means for releasing the clutch to disconnect the slide carrying conveyor from the automatic intermittent drive mechanism.

Fig. 4 is a front detail view, partly in section, of the rotatable light border interrupting means, and

Fig. 5 is a rear view of Fig. 4, also partly in section, showing the mounting of the border producing screen and the means for laterally adjusting the supporting bracket on the frame of the main stereopticon machine.

10 In the drawings, the portions indicated as A, represent the base or table on which the machine, as a whole, is mounted; B indicates the glass slides on which the advertising matter is displayed in any desired manner, 15 C and D represent the adjustable projection lenses, and E represents an electric motor. All of these parts may be of any well known or approved design or construction, providing they do not depart from the spirit of 20 the invention hereinafter to be described.

The base or table A is preferably formed of wood, although any light metal such as aluminum, may be substituted, which will rigidly support the main structural frame of 25 the stereopticon machine in use. The main structural or supporting frame consists of two substantially rectangular castings 2 and 3, having legs 4 and 5 which are secured to the base A by machine screws or bolts 6. 30 Each of the castings 2 and 3 are suitably reinforced and provided with integral web portions 7 and 8 respectively, the inner flanged extremities of which are secured together by machine screws 9. These flanged web portions, when bolted together, serve to uniformly space the castings and rigidly secure the frame sections in aligned spaced relation, as is clearly shown in Fig. 1.

At each of the four corners of the castings 2 and 3 the frame is enlarged to provide bearings for transverse shafts 10 on each of which a pair of spaced sprocket wheels 11 and 12 are secured to rotate with the shafts. A slide-holder conveyor, consisting 45 of a pair of endless sprocket chains 13 and 14, is carried on the sprocket wheels 11 and 12, and is adapted to be adjusted, for slack, by means of the radially adjustable bearing holder 15, shown in Fig. 1. The conveyor 50 also comprises an endless series of overlapping slide holders 16, which extend between the spaced sprocket chains and are rigidly secured to every fifth link of each chain, as is clearly illustrated in Fig. 2. The slide 55 holders are preferably formed by castings to provide overlying edges and channel ways 17, into which the glass slides B are adapted to fit. A boss or stop 18 is also cast integrally with one side of the rectangular slide holder 60 to limit the movement of a slide, when inserted in the channels 17, and a spring leaf 19 is secured to the stop 18, to frictionally hold and engage a slide in position against the stop. Extending at substantially right 65 angles to the rear or under face of each slide

holder 16, are a pair of spaced link-shaped webs 20 which are rigidly secured to a link in each of the sprocket chains 13 and 14 by rivets 21. Each slide holder thus forms a rigid part of a link in each chain, causing 70 the chains to travel in synchronism and thereby always maintaining parallel relationship between the slide holders in operation.

The contiguous edges of slide holders are 75 provided with oppositely inclined flanges which overlap to form co-operating shutter elements 22 and 23 for excluding passage of light between the slide holders during their intermittent travel through the optical axis 80 of the machine.

The forward stanchions 24 and 25, of the frame members 2 and 3, are formed intermediate their extremities to provide a box-shaped recess therebetween, to receive the 85 condenser lens holder 26, and to provide a perpendicular face 27 on which the slide holder conveyor is adapted to slide, to axially position a slide B relative to the condenser lenses 28 and 28', see Fig. 2. Secured to each of the stanchions 24 and 25, on each side of the conveyor chains 13 and 14, are bracket members 29 and 30, adapted to adjustably support an adjustable projection lens C in axial alignment with the condenser lenses 28 and 28'.

The stanchion 24, of the casting 2, is formed with a laterally extending shelf portion 31 having an elevated platform extension 32 on which the electric motor E is adjustably mounted by bolts 33. A gear box 34 is removably mounted on the shelf portion 31 by machine screws 35, and contains the intermittent drive mechanism for the slide holder conveyor to be described hereafter.

The transverse shaft 10', journaled in the lower extremities of the stanchions 24 and 25, of the castings 2 and 3, extends through the stanchion 23 and a clutch element 36 having a sleeve portion 37 is secured on the end of the shaft 10', by a pin 38.

A tubular drive shaft 39 extends transversely through the gear box 34, coaxial to the shaft 10' on which the conveyor driving sprocket wheels 11' are secured. A clutch element 40 is secured on the end of the shaft 39 adjacent the clutch element 36 and carries an axially movable, spring pressed key 41, which is adapted to enter a transverse slot 42 in the face of the clutch element 36. The clutch elements 36 and 40 and key 41 co-act to provide what I will term a definite relation clutch. A rod 43, secured to the key 41, extends through the tubular drive shaft 39 and is provided with a knob 44, at its outer extremity, whereby the key 41 may be manually retracted from the slot in the face of the clutch element 36 to disconnect the shaft 10' from the inter- 125

mittent drive mechanism now to be described.

The rotary shaft 45 of the motor E is connected to a shaft 46, which extends into the gear box 34, by a shaft coupling 47. A small pinion gear, not shown, is carried on the shaft 46, within the gear box, and meshes with the larger driven gear 48 on the worm gear shaft 49. Extending transversely through the gear box below the worm gear shaft 49 is a shaft 50 on which is carried a gear 51, which meshes with and is driven by the worm gear shaft 49. The elements 52 and 53 of the Geneva gear movement are mounted respectively on the shaft 50, and the tubular shaft 39, and co-operate to turn the shaft 39 and coaxial shaft 10', through the clutch elements 40, 41 and 36, a quarter of a turn on each revolution of the gear element 52. The sprocket wheels 11' are thus caused to advance the slide carrier conveyor a distance equal to the width of a slide holder on each revolution of the gear element 52. It will also be noted that, when the key 41 of the "definite relation clutch" is retracted from the slot in the face of the element 36, by manual operation of the spring pressed rod 43, to free the slide conveyor from its automatic drive mechanism, the clutch elements will not re-engage to restore the drive to the slide conveyor until the slide conveyor and drive mechanism are in a predetermined definite relation.

35 Adjustably mounted on the two lower horizontal frame members of the castings 2 and 3, is a bracket member 54 having a centrally arranged clamping yoke 55 which is adapted to receive and rigidly support a standard 56. Universal clamping bracket members 57 and 58 are adjustably mounted on the standards 56 in which arms 59 and 60, carrying a lamp socket and reflector, respectively, are adjustably mounted.

45 The above description relates to the specific details of construction of the main stereopticon machine including the means for automatically and intermittently advancing the endless slide conveyor on the main frame.

50 The stanchion 24 of the main frame is further provided with a supporting face 63 having rearwardly extending spaced lugs 64 and 65 formed with threaded apertures 66 and 67.

55 An animated border projecting stereopticon unit, now to be described, is adapted to be adjustably secured to the face 63 of the stanchion 24 to form a rigid part of the main stereopticon.

60 This unit comprises a substantially L-shaped bracket member 68 provided with a depending, rearwardly extending, arm 69 and a supporting rod 70 secured to the end 65 of the arm 69. The bracket 68 is formed

with a pair of spaced, rearwardly extending lugs 71 and 72, carrying adjusting screws 73 and 74 which co-operate with the threaded apertures 66 and 67 in the lugs 64, and 65, see Fig. 5. The screws 73 and 74 are rotatably mounted in apertures in the lugs 71 and 72 and retained by washers 75 and 76 which are secured to the screws by pins 77 and 78. The bracket 68 may thus be laterally adjusted to focus the border projection unit 75 relative to the main stereopticon, and the bracket arm 79 secured at one end to the light supporting bracket 54, is provided with a slotted end portion 80, in which the end of the supporting rod 70 is adjustably secured 80 by a screw 81, to retain the bracket 68 and co-operating elements in adjusted position. A lamp socket 82 and reflector 83 are adjustably mounted on the supporting rod 70.

Secured on the bracket 68 is a pair of vertically spaced frame members 84 and 85 each being provided with a spring-pressed lever member 86 and 86' pivoted at the upper edge of said frame members and adapted to frictionally engage and retain a pair of condenser lenses 87 and 87' in position on said frame.

85 A pair of spaced pins 88 project inwardly from the frame member 84 on which a perforated border-producing screen member 89 is hung and centered on the frame member 84, beneath the spring-pressed condenser lens 87, see Fig. 4.

90 The screen 89 is preferably formed of thin sheet metal and is perforated as at 89' to permit passage of light from the condenser lens 87 to produce an illuminated border around and concentric with the optical projection of the main stereopticon machine.

95 On the forward edge of the bracket 68 is secured an annular frame member 90 carrying roller bearings 91, which serve to rotatably support a light-interrupting means 92 which co-operates with the stationary perforated screen 89 to produce an animated or traveling light border which will be understood from the following:

100 The light-interrupting means 92, as shown in Fig. 4, consists in a pair of ring-shaped members 93 and 94 having tubular flange portions which are screw-threaded together through the annular frame member 90. A color screen 95, formed of glass, and a radially slotted screen 96, formed preferably of thin sheet metal, are clamped between the threaded sleeve portions of the rings 93 and 94 to rotate therewith. The ring member 93 is formed with teeth 97 on its periphery which mesh with the teeth of a gear wheel 98 journaled in the bracket 68 to rotate in a horizontal plane below the condenser lens frames 84 and 85.

105 110 115 120 125 130 The gear 98 is secured to the upper end of a vertical drive shaft 99 which shaft is journaled in a bracket 100 mounted on the side

of the gear box 34. The shaft 99 is provided with a universal joint 101 between the fixed bracket 100 and the adjustable bracket 68, and a worm gear 102 which meshes with the gear 103 carried on the end of the shaft 50 extending through a wall of the gear box 34.

The light interrupting means 92 is thus driven by the motor E through the gearing previously described.

10 A pair of bracket members 104 are secured on opposite sides of the frame members 84 and are adapted to adjustably support an adjustable projection lens D in axial alignment with the condenser lenses 87 and 87'.

15 What is claimed is:

1. In a stereopticon apparatus the combination of a projector, a slide carrier driving means, means for intermittently advancing and locking said driving means at predetermined intervals, and means operable to disconnect said driving means from said advancing and locking means and to connect said driving means with said advancing and locking means in a predetermined definite relation upon re-engagement.

2. A stereopticon apparatus comprising optical projection means, an endless slide conveyor mounted to successively present slides into the optical axis of said projection means, driving means for said conveyor, automatic means positively connected to said slide conveyor driving means for successively and intermittently advancing the slides into the optical axis of said projection means at predetermined intervals and locking said slide conveyor in advanced positions, and a definite relation clutch operable to disconnect said slide conveyor driving means from 40 said automatic means.

3. A stereopticon apparatus comprising optical projection means, an endless slide carrier operating means, motor operated means operatively connected to intermittently drive said slide carrier operating means to present and lock successive slides at predetermined intervals in the optical axis of said projection means, and means interposed between said motor operated means and said slide carrier operating means for rendering the operation of said motor operated means ineffective when the slide carrier is to be manually operated, said means operating when released to automatically reestablish driving connection between said motor operated means and said slide carrier operating means in a predetermined definite relation.

4. A stereopticon apparatus comprising optical projection means, an endless slide carrier operating means, motor operated means operatively connected to intermittently drive said slide carrier operating means to present and lock successive slides at predetermined intervals in the optical axis of said projection means, and clutch

means interposed between said motor operated means and said slide carrier operating means, said clutch means co-operating with said slide carrier operating means and driving means to automatically connect said slide carrier with said driving means in a predetermined definite relation.

5. In an intermittently operated stereopticon apparatus, the combination of a slide carrier drive, a motor, a Geneva gear movement driven by said motor, and a definite relation clutch element interposed between said Geneva gear movement and said slide carrier drive.

6. A stereopticon apparatus comprising a supporting frame consisting of a pair of substantially rectangular castings secured together in spaced relation by intermediate web portions, sprocket wheels journaled between said castings, an endless slide conveyor mounted on said sprocket wheels, a projector adjustably mounted within said supporting frame to project between said spaced castings, said castings co-operating at one end to provide a vertical face over which said slide conveyor slides to align the slides during their intermittent travel through the optical axis of said projector, and motor operated means mounted on one of said castings and connected to one of said sprocket wheels for driving said slide conveyor.

7. A stereopticon apparatus of the class described comprising a pair of vertically supported frame castings each being formed with co-operating web portions secured together to uniformly space and brace said frame castings, sprocket wheels journaled between said frame castings, an endless slide conveyor mounted on said sprocket wheels, an optical projector adjustably mounted on said frame castings, and motor operated means mounted on said frame castings and operatively connected to intermittently drive said slide conveyor to present and lock successive slides of said slide conveyor in the optical axis of said projector.

8. A stereopticon apparatus for advertising or other purposes, comprising a rigid frame, an optical projecting means adjustably mounted on said frame, an endless slide carrier mounted on said frame, motor operated means for intermittently advancing successive slides of said slide carrier into the optical axis of said projection means, a second optical projection means adjustably mounted on said frame, a traveling light border-producing means carried thereby, and means for continuously operating said light border-producing means from said motor operated means for intermittently advancing said slide carrier.

9. In combination with an automatic stereopticon apparatus of the class described, having a rigid frame, a second optical pro-

jection unit, said unit comprising a bracket on which optical projection means is mounted, and means on said bracket co-operating with means on said frame for adjustably securing said bracket relative to said frame.

10. A stereopticon apparatus, comprising a rigid frame, optical projection means adjustably mounted on said frame, an endless slide carrier mounted on said frame, means for intermittently advancing successive slides of said slide carrier into the optical axis of said projection apparatus, and shutter means carried by said slide carrier for intercepting the passage of light between successive slides during their intermittent travel through the optical axis of said projection apparatus.

11. A stereopticon apparatus comprising a rigid frame, optical projection means adjustably mounted on said frame, an endless slide conveyor mounted on said frame to traverse the optical axis of said projection apparatus, means for intermittently driving said conveyor, slide holders rigidly secured to said conveyor, said slide holders having their contiguous edges formed to provide shutters to exclude passage of light between successive slides during their intermittent travel through the optical axis of said projection apparatus. 20 25 30

In testimony whereof I affix my signature.

ADMIRAL S. KNOTT.
